CLAIM

We claim the ornamental design for a display screen or portion thereof with a vascular position icon, as shown and described.

DESCRIPTION

The patent or application file contains at least one drawing executed in color. Copies of this patent or patent application publication with color drawings will be provided by the Office upon request and payment of the necessary fee.

The sole FIGURE is a front view of a display screen or portion thereof with a vascular position icon with an orange background showing our new design.

The portions of the drawings shown in broken lines illustrate a display screen or portion thereof and form no part of the claimed design.
